UNITED STATES PATENT OFFICE.

EMIL HOLLENDER, OF NEW YORK, N. Y.

BOTTLE-STOPPER.

SPECIFICATION forming part of Letters Patent No. 228,355, dated June 1, 1880.

Application filed April 28, 1880. (No model.)

To all whom it may concern:

Be it known that I, EMIL HOLLENDER, a citizen of the United States, residing at New York, in the county and State of New York, 5 have invented new and useful Improvements in Bottle-Stoppers, of which the following is a specification.

This invention consists in the combination, in a bottle-stopper, of a neck-band provided 10 with an eye on one and with a bar on its opposite side, and a bail provided on one side with a rod which engages with and is constructed to swivel in the eye of the neck-band, while on the opposite side of the bail is formed 15 a hook-lock, which, when the bail is swung over the stopper, serves to lock the same and to depress it firmly upon the stopper.

This invention is illustrated in the accompanying drawings, in which—
20 Figure 1 represents a side view of my bottle-stopper when the bottle is closed. Fig. 2 is a front view of the same. Fig. 2* is a plan or top view of the same. Fig. 3 is a front view when the bottle is open. Fig. 4 is a horizontal section of the same in the plane xx , Fig. 3.

Similar letters indicate corresponding parts.

In the drawings, the letter A designates a bottle, which is closed by an ordinary stopper, B, of cork or any other suitable material.

The means which I employ to retain the stopper securely in position consists of a bail, C, and neck-band D.

The neck-band is provided on one side with 35 an eye, a, and on its opposite side with a bar, b, and it is secured on the neck of the bottle in any suitable manner.

The bail C is, by preference, constructed of a single piece of wire, and it is provided on 40 one side with a rod, c, and on its opposite side with a hook-lock, d, the rod and the arm which carries the hook-lock being parallel to each other and connected by the top bar, e, which is curved, as shown in Fig. 2*. The rod c extends through the eye a of the neck-band, and it is provided with a head, which prevents it from slipping up through said eye. In the example shown in the drawings this head is made by bending the end of the

rod to form an eye or ring, which may be situated below the eye a, or which may be made to engage with the same; but said head may be produced in any suitable manner. The rod c easily slides and turns in the eye a.

The hook-lock d is produced by bending the 55 wire which forms the bail in the manner shown in Fig. 1, the part f of the hook being slightly inclined, so that when the bail is swung over the stopper the incline f readily catches beneath the bar b of the neck-band, and by pressing said incline inward to the position shown in Fig. 1 the bail is firmly depressed upon the stopper and locked in its closing position.

When the bottle is to be opened the hook-lock d is forced back, so as to become disengaged from the bar b; and in order to permit this operation the rod c must swivel in the eye a, and as soon as the bail has been swung around to the position shown in Fig. 3 the stopper can be readily withdrawn, or, if the 70 bottle is filled with an effervescent liquid under sufficient pressure, the stopper is forced out automatically as soon as it is no longer retained by the bail.

By this arrangement the bail is always in 75 position to be swung over the stopper and to lock the same when the bottle is closed, and when the bottle is empty the bail is not in the way of cleaning the bottle.

What I claim as new, and desire to secure 80 by Letters Patent, is—

The combination, in a bottle-stopper, of a neck-band provided with an eye on one side and with a bar on its opposite side, and a bail provided on one side with a rod which 85 engages with and is constructed to swivel in the eye of the neck-band, while on the opposite side of said bail is formed a hook-lock, constructed to engage with the bar of the neck-band, substantially as and for the purpose 90 shown and described.

In testimony whereof I have hereunto set my hand and seal in the presence of two subscribing witnesses.

EMIL HOLLENDER. [L. s.]
